Patented Sept. 30, 1975

237,020

COMBINED SUPPORT AND STORAGE TRAY FOR AN EDUCATIONAL KIT OR SIMILAR ARTICLE

Charles G. Valentine, Stamford, Conn., assignor to
Xerox Corporation, Stamford, Conn.

Filed Feb. 26, 1973, Ser. No. 335,638

Term of patent 14 years

Int. Cl. D3—99

U.S. Cl. D87—1 R

FIG. 4

FIG. 2

FIG. 3

FIG. 1 is a top perspective view of a combined support and storage tray for an educational kit or similar article showing my new design;

FIG. 2 is a rear elevational view thereof;

FIG. 3 is an elevational view looking from the right of FIG. 2; and

FIG. 4 is a front elevational view thereof.

I claim:

The ornamental design for a combined support and storage tray for an educational kit or similar article, substantially as shown.
